UNITED STATES PATENT OFFICE.

MAX MEIROWSKY, OF PORZ, GERMANY.

PROCESS FOR MAKING MICA PLATES.

1,163,434.

Specification of Letters Patent.

Patented Dec. 7, 1915.

Application filed August 15, 1912. Serial No. 715,197.

To all whom it may concern:

Be it known that I, MAX MEIROWSKY, a subject of the King of Prussia, and resident at Porz, in the Province of the Rhine, 5 Kingdom of Prussia, German Empire, have invented a certain new and useful Process for Making Mica Plates, of which the following is a specification.

In the preparation of mica plates it is old 10 to lift the particles of mica by means of a movable sieve placed under the action of aspirated air which lifts them off the conveyer band, and delivers them to the strips to be covered. This process and the devices 15 already known for the carrying out thereof, possess the drawback that the particles of mica are not sufficiently separated from one another during the short passage from the conveyer band to the sieve. Several very 20 thin particles frequently stick together, especially in damp air, and in view of their thinness one can never be sure whether one or several particles thus adhere. If, however, several particles lying one upon another 25 are brought upon the strip to be covered, the connection of the various layers is naturally a very imperfect one. Further, it is a drawback in this construction that special attendants or apparatuses are necessary 30 in order to supply the mica to the conveyer and to distribute it upon it somewhat uniformly. This is, however, important if it be desired to produce an article of uniform good quality. If a band of greater width 35 has to be produced, then especial attention is necessary in order that the conveyer band may be uniformly covered. As it is difficult to control the uniformity of the product, one is obliged to rely entirely upon the accuracy 40 of the operator, which nevertheless frequently proves unsatisfactory. In consequence of the continuous working of the machine, the workman must not turn away his attention for an instant if he is to avoid irregularities in the covering of the strip. These 45 drawbacks render it advisable that the supply of the mica to the movable sieve should also be effected automatically and as far as possible to arrange it in such a manner that the particles on their way to the sieve should 50 be scattered one from another and be uniformly distributed over the surface of the sieve. In accordance with the invention this aspiration action is not only devised for the holding fast of the particles when brought 55 in the neighborhood of the sieve to its sur-

face, but also the particles themselves are to be sucked out of their receptacle, and the distance from the receptacle to the sieve is made so long that the particles have time 60 during the transit to separate one from another. The sub-division is obtained more effectively, especially in damp air, when aspirated air is used. Moreover the air used can be brought again into the receptacle in 65 order thereby to stir up and to dry the mica therein.

The present invention also enables me by suitable proportioning of the apertures of the sieve to aspirate the dust and the little 70 particles out of the mass. The dust and small particles are drawn by the fan through the sieve, which sorts them, to a collector. This is of especial importance in the construction of plates of the kind which are 75 used for the construction of insulating plates for accumulators. Moreover the insulating of all plates is greatly improved by this process.

The drawing illustrates a construction 80 suitable for the carrying out of the invention as follows:

Figure 1 shows a longitudinal section. Fig. 2 a plan view of the device.

In these drawings *a* denotes the receptacle 85 from which the mica flakes can be drawn. Attached to the receptacle over the whole width thereof, is a closed channel *b*, which descends to the movable sieve *d* traveling over rollers *c*, the rollers receiving their motion by means of worm gearing from a motor. The sieve *d* is placed vertically to the longitudinal axis of the channel *b*. On the rear side of the sieve the channel is prolonged 90 above the partition wall *i* in the suction tube *e*, which leads to the fan *f*. The air, preferably warmed, passes into the receptacle *a* through a slot *g* over against the channel *b* and extends across the whole width of the receptacle. The air also is driven into 100 the container *a* from below by the fan as indicated by the arrows in Fig. 1, and passes through a heater *m* and the perforated bottom *a'*, so that the particles in the receptacle may be somewhat stirred up and at the 105 same time dried and heated.

The method of working is as follows: The air aspirated by the fan *f* flows through the slot *g* above the uppermost layer of the mica in the receptacle *a* and carries with it the 110 particles through the long channel *b* until they remain adherent to the sieve *d*. In con-

2
sequence of the stirring up in the receptacle and the channel, the little particles are separated from one another and are well distributed on the sieve. From the sieve the flakes fall on the band b , which can be arranged in any convenient manner. As a relatively large surface of the sieve passes through the air channel b , a very uniform covering takes place. As soon as one hole of 5 the sieve is covered it no longer can act and the particles seek out other uncovered holes. This advantage also was not attained in the hitherto used system of covering by means 10 of a transporting band, because in this case there was always only a narrow strip of the sieve passing at the receiving point and consequently frequently several holes remained 15 uncovered.

The device can also be worked by means of

pressure air instead of suction, although the 20 advantages in this case do not equal those of the method above described.

Having now described my invention, what I claim and desire to secure, is:

A process of feeding mica sticking machines with the aid of aspirated air which 25 consists in causing the flake of mica to be driven against screening means by said air, and then deposited upon the adhesive plate, the air being heated while passing to the 30 mica receptacle through a heating zone.

In testimony, whereof I have signed my name, to this specification, in the presence of two subscribing witnesses.

MAX MEIROWSKY.
